(57) **CLAIM**

The ornamental design for an expandable shoe rack, as shown and described.

DESCRIPTION

FIG. 1 is a perspective view of the expandable shoe rack showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the expandable shoe racks are stacked.

The broken lines in the figures illustrate portions of the expandable shoe rack that form no part of the claimed design.
